UNITED STATES PATENT OFFICE.

ELI TIFFANY, OF BENNINGTON, VERMONT.

IMPROVEMENT IN KNITTING-MACHINE-NEEDLE CYLINDERS.

Specification forming part of Letters Patent No. 149,811, dated April 14, 1874; application filed May 6, 1873.

To all whom it may concern:

Be it known that I, ELI TIFFANY, of Bennington, in the county of Bennington and State of Vermont, have invented an Improved Knitting Machine; and I do hereby declare that the following, taken in connection with the drawings which accompany and form part of this specification, is a description of my invention sufficient to enable those skilled in the art to practice it.

The invention relates particularly to the organization of a machine for knitting tubular cord or small tubular work, the machine being particularly intended as a toy, or for the use of children, although more or less applicable to the manufacture of cord for utilitarian purposes.

In my machine I use a bed-plate, preferably made with a clamp device for attachment to the edge of a table, and at one end of this plate I fix a vertical tube, of lead or soft metal, having in its outer surface a series of radial grooves, in which the shanks of the needles play, the tube being shouldered, and having a spring encompassing it above the shoulder to hold the needles in place as they slide, and being bushed with brass or other composition of harder metal than that of the grooved needle-tube for a guide through which the work is to be drawn, and being encompassed by a rotary yarn-carrier and guide and needle-operator, at the foot of which is a pulley resting upon the plate, and belted to a driving-pulley at the opposite end of the plate.

In constructing the needle-tube and uniting it to the bed-plate, I cast the tube of soft metal, and with the bore to a general and uniformly cylindric shape from end to end. The upper end I cast around a projecting guide-tube, the cylinder being, moreover, cast with a series of needle-shank grooves extending radially into it. The needle-shanks slide in these grooves, and, to confine them in position for their slide movements, the cast cylinder is turned down at the upper part to form a shoulder to receive a ligature spring, while at its bottom part the cylinder is turned down, to enter a socket cast in the bed for its reception, and to form a shoulder to set upon the bed. The invention consists in a knitting-machine

having a needle-shank tube thus formed and united to its bed.

The drawing represents a machine embodying my construction.

Figure 1 shows the machine in plan. Fig. 2 is a side elevation of it. Fig. 3 is a cross-section through the center of the tube. Fig. 4 shows the needle-tube in elevation above the base-plate.

a denotes the base-plate; *b*, the arm, and *c* the screw by which the plate is clamped to a table. Near one end of the plate rises the tube *d*, in which are formed the vertical and radial grooves *e*. The upper part of the tube is made smaller than the main part, and around the smaller part *f*, and upon or just above the shoulder *g*, is an annular spring, *h*, encompassing the needle-shanks, and keeping them in place as they reciprocate vertically. The needles *i* are ordinary latch-needles, each having a hook, *k*, and a latch, *l*, and the shanks of these needles play in the grooves *e*. The tube *d* is bushed with the composition tube *m*, and through this tube is drawn the work formed upon and by the needles. Encompassing the tube and its grooves is the rotating thread-carrier and guide *n*, and through this tubular guide is cut the cam-groove *o*, into which extend the butts of the needles, rotation of the tube *n* successively effecting the alternate rise and fall of the respective needles. At the bottom of this tube is the grooved pulley *p*, formed as a part of the tube, and this pulley is belted by a band, *q*, with another and driving pulley, *r*; rotation of the pulley *r* effecting the rotation of the pulley *p* and the resulting action of the needles. *s* denotes the yarn-spool pin or spindle; *t* *t'*, the guiding-eyes, through which the yarn passes from the spool to the needles. *u* is an arm, having a guide-eye, *v*, through which and the eye *w* a core of yarns or strands, *x*, may pass, to be enclosed in the tubular structure or fabric formed by the needles. *y* denotes the weight, by which the work is drawn down as the loops are successively formed and interlocked. The eye *t* is placed with such relation to the paths of movement of the needles that the yarn is laid over the open needle-latch, and is kept over such latch without possibility of slipping be-

neath it. When the needle slides down, the loop around its shank extends from the top edge of the tube *m*, and as the latch reaches it it throws up the latch, and the hook then draws the yarn (to form a new loop) down through the first loop, the first loop slipping over the latch and hook, and being drawn into the tube by the weight or tension upon the work. As the needle next rises to again receive the yarn laid into its hook, the loop within the hook, stretched over the edge of the tube *m*, is met by the latch, and the latch is thereby opened, being thrown open and held down by the loop, and leaving the hook ready to receive the yarn thrown into it, or against the needle-shank.

By this construction no special devices are needed to open or close the latches or needle-hooks, the strain of the yarn, the position at which the yarn is thrown across the needle-shanks, and the position of the top of the tube *m*, insuring the opening and closing of the latches at the proper times.

When the tube is to be knit around the core or central yarns, the end of said core is sim-

ply presented to the mouth of the tube against the yarn, when it will be drawn in by the stitches, progressing as the knitting progresses.

The construction of the tube will be understood from inspection of Figs. 5, 6, 7, and 8. Fig. 5 shows the tube as first cast; Fig. 6, its form when reduced; Fig. 7, a cross-section of it on the line *x* *x*; Fig. 8, a section on the line *y* *y*. The tube is first cast in the uniform cylindrical form, and with the radial grooves, as seen in Figs. 5 and 7, it being also cast around the guide-tube *m*, as shown in Fig. 8. The tube, having been thus cast, is turned down at each end, as seen in Figs. 6 and 8, its shouldered bottom end entering the bed, and its upper end receiving the spring *h*, as shown in Fig. 3.

I claim—

The knitting-machine needle-shank cylinder or tube *d*, cast with the grooves *e* and upon the guide-tube *m*, and then turned down at the ends to be applied to the bed, and to receive the needle-holding ring.

Witnesses: ELI TIFFANY.
